AMOS RANK, OF SALEM, OHIO.

Letters Patent No. 77,526, dated May 5, 1868.

IMPROVEMENT IN HARVESTERS.

The Schedule referred to in these Letters Patent and making part of the same.

TO ALL WHOM IT MAY CONCERN:

Be it known that I, AMOS RANK, of Salem, in the county of Columbiana, and State of Ohio, have invented certain new and useful Improvements in Reaping-Machinery; and I do hereby declare that the following is a full, clear, and exact description thereof, reference being had to the accompanying drawings, making part of this specification, in which—

Figure 1 is a perspective view of a reeling and dropping-attachment having my improvements applied to it.

Figure 2 is an elevation of the inner side of such attachment, showing the improved belt-tightener.

Figures 3 and 4 represent the grain-wheel, and the method of attaching it to the outer divider.

Figure 5 is a view of the grain-side of the inner divider, showing the manner of adjusting it.

Similar letters of reference indicate corresponding parts in the several figures.

This invention relates to certain new and useful improvements on reaping-machinery, wherein the finger-bar is hinged in such manner that it will vibrate and also rise and descend bodily, so as to accommodate itself to the undulations of the ground over which it is drawn, and wherein a slatted dropping-platform is employed, in conjunction with a grain-guard or fender, for the purpose of effecting the discharge of the cut grain from the platform in gavels by the action of the stubble alone, and wherein the reel, for gathering in the standing grain to be cut, is supported at its inner end by means of a post, which is sustained by and allowed to move in harmony with the finger-beam.

The nature of my invention consists in providing the endless chain or belt which communicates motion to the reel with a simple device, which will always keep said belt under proper tension and prevent it from slipping; said device consisting of an angular arm, which is pivoted to the reel-post, and which carries on one end a grooved wheel, that is pressed against the belt or chain by means of a spring-strap; acting upon the opposite end of this arm during the rising and falling movements of the platform and consequent changes in relation of the reel-pulley to the driving-pulley of the main or draught-frame. Thus, with a single tension-pulley and a simple angle-lever and a cheap spring, all applied in a simple and convenient way, the belt which drives the reel will be kept "taut" under all gyrations of the hinged finger-beam and platform on which the reel is mounted, as will be hereinafter described.

The invention also consists in attaching the inner divider or gathering-board to the reel-post, by means of an angular bracket, in such manner that the front end of this divider can be readily adjusted higher or lower, according to the character of the grain to be cut, as will be hereinafter described.

To enable others skilled in the art to understand my invention, I will describe its construction and operation.

In the accompanying drawings, A represents the inner shoe, which is adapted for being hinged to the rear end of an inclined drag-bar upon a main draught-frame, and also for being attached to said frame by means of an inclined transverse hinged brace. To this shoe, A, the finger-bar B and a standard, a, are rigidly bolted, as shown in figs. 1 and 2. This shoe, A, is also constructed with an open bearing, b, for receiving a rocking-pin which is upon the inner end of the platform-bar C.

The outer end of the finger-bar B has a shoe, D, rigidly secured to it, which is constructed with an eye-bearing, b', for receiving a rocking-pin, upon the outer end of the platform-bar C. This shoe, D, has a hollow slotted standard, c, bolted to it, the upper end of which is bent at an angle, so as to receive upon and have bolted to it the divider-guard E' of the divider E. This divider is suitably bolted to the shoe D, and secured to the guard E' and shoe-extension E'', which latter is bolted to the toe of the metal shoe D, as shown in fig. 3. The slotted standard c has a slide, e, secured to it by means of a bolt, the head of which is between this standard and the divider E, so that, while this bolt cannot be drawn out of the slot in the standard, it will, when loosened, allow the outer end of the finger-bar to be adjusted nearer to or farther from the ground, according to the height of cut required. To the front part of the slide e an arm, F is hinged, by means of a vertical pin passed through ears which are formed on said slide, as shown in fig. 3. The arm F is curved, as shown, and has a short axle secured to it, upon which is the grain-wheel G. Just in rear of the hinge of the arm F, a stud,

g, is affixed to it, which stud is arranged upon the inner side of its arm, and made of sufficient length to abut against the slide *e* when the arm *F* is brought at right angles to the finger-bar, as shown in fig. 4. This stud, *g*, will thus prevent the wheel *G* from striking against the shoe *D* or the outer divider *E*, but allow it to swing outward freely.

To the inner side of the standard *a* the reel-post *H* is secured by means of two bolts, the lower one of which serves as a pivot for allowing the post to be inclined more or less, and the upper bolt passes through a slot which is made through standard *a*, concentric to the axis of the lower bolt, for the purpose of securing the post rigidly in place when it is adjusted to the position required. Upon this post, *H*, a collar, *I*, is slipped, which can be secured in place at different heights from the bottom of the post by means of a set-screw, *i*. This adjustable collar, *I*, is constructed with an eye-bearing, for receiving the short shaft *J* of the reel *J'*, and also with two ears, *j*, projecting from its rear side.

On the inner end of the reel-shaft *J* a grooved pulley or chain-drum, *h*, is keyed, around which a belt, *k*, passes, which belt also passes behind and under the grooved pulleys *h'*, near the lower end of the reel-post, and from thence to a pulley on the axle of a main frame, or on a pulley which derives its motion from the drive-wheels of the harvester, as shown in figs. 1 and 2. Between the pulleys *h* and *h'* is a grooved wheel, *k*, which is pressed forward against the belt *K*, so as to keep this belt under proper tension, by means of an India-rubber strap, *l*, acting upon the arm of an angular lever, *m*, which is pivoted to the reel-post *H*, as shown, and which carries said grooved wheel, *k*, as shown clearly in the drawings. The spring *l* will keep the wheel *k* in contact with the belt *K*, and this will keep the belt tight, without dragging upon it or creating undue friction during the rising-and-falling movement of the platform on its hinge-joint connections, and consequent change in the relation of the reel-pulleys to the driving-shaft pulley.

To the ears *j*, upon the adjustable collar *I*, the bifurcated ends of a bent rod, *L*, are pivoted, so as to allow this rod to vibrate freely in a vertical plane. The lower end of the rod *L* is bent outward, and has a guard or fender-bar, *L'*, secured to it, which extends transversely across the platform *C'*, and serves to catch the falling grain during the act of discharging grain from said platform. Near the pivoted ends of the rod *L*, and upon this rod, is an adjustable collar, *p*, to which is secured, by a pivot-joint, the upper end of a connecting-rod, *M*, the lower end of which is pivoted to an arm, *v*, projecting from the inner pivot-pin of the platform-bar *C*. The rod *M* has several holes through it, at and near its upper extremity, for the purpose of lengthening or shortening the distance between its two points of connection.

When the platform is raised to a position for collecting cut grain upon it, the rod *M* will throw the guard *L'* up out of the way of the grain as it falls upon said platform, and when the platform is allowed to drop upon the stubble for discharging its load, the guard will be simultaneously brought down to a position for receiving the falling grain, and preventing this grain from reaching the platform during the discharging-operation.

It will be seen that the platform or grain-receiver *C'* is composed of slats, arranged at proper distances apart, and secured at right angles to the beam *C*, so that when this platform is allowed to drop upon the stubble, the latter will carry of any grain which may be upon it.

The inner divider or gathering-board *P* is arranged on the outer side of the reel-post *H* and standard *a*, and it is sustained in proper position by means of an angular bracket, *T*, which is shown in fig. 5, also in fig. 1. This bracket, *T*, is bolted rigidly to the post *H*, and the board *P* is secured to it by means of two bolts, *s s'*, one of which passes through a curved slot, *t*, made through the board, and the other serves as a pivot to allow the front end of said board to be raised or depressed when the bolt *s'* is loosened.

Having described my invention, what I claim as new, and desire to secure by Letters Patent, is—

1. The combination, in a belt-tightener, of the angular lever *m*, spring *l*, and the grooved wheel *k*, substantially as and for the purpose described.
2. Applying the inside divider *P* to a bracket, *T*, upon the reel-post *H*, and making this divider adjustable, substantially as described.

AMOS RANK.
